TAPE SERVING APPARATUS, INCLUDING DIRECTIVE ADVANCING AND MOISTENING MEANS THEREFOR

Trevor R. Gautier, Nashua, N. H., assignor to
Nashua Gummed and Coated Paper Company,
Nashua, N. H., a corporation of Massachusetts

Original application November 29, 1938, Serial No.
242,936. Divided and this application February
26, 1940, Serial No. 320,849

7 Claims. (Cl. 91—38)

This invention relates to machines and apparatus for serving or dispensing strip material, particularly gummed tape, in desired lengths, and is more especially concerned with improved means for moistening and delivering the strips or tape lengths in condition for application in packaging and other uses for which such material is adapted. One machine of the general class to which this invention is applicable is shown in my prior Patent No. 2,082,733, dated June 1, 1937, the present invention being in various respects an improvement in tape conducting, moistening and delivering mechanism of the character as there shown.

This application is a division of my copending application, Serial No. 242,936, filed November 29, 1938, now Patent No. 2,192,132, dated February 27, 1940.

In the drawing illustrating by way of example one embodiment of the invention,

Fig. 1 is a partial longitudinal vertical section centrally through the machine; and

Fig. 2 is a plan, on a smaller scale, of the delivery end of the machine, with the cover open.

Referring to the drawing in more particular, the machine as a whole comprises a housing including side frames 1 secured in spaced relation as by suitable cross ties, two of which are seen at 2, 2, in Fig. 1. A roll supply S of the strip material to be dispensed, such as gummed paper tape, is supported in a well 6 at the rear of the housing, by means of a series of transverse rollers, two of which are seen at 7, 7 in Fig. 1. The machine is adapted to handle various different widths of tape, the roll supply S being positioned transversely between laterally adjustable guide plates, a portion of one of which appears at 8. Keyhole slots 9 in the plates have reduced portions engageable in selected circumferential grooves in cross rods 10, to hold the plates in selected position similarly as in my prior patent. The rod 10 seen in Fig. 1 is rotatably supported between the side frames, adapting it to serve also as a guide for the tape T coming from the supply.

The tape T is led forwardly from the roll supply past the guide 10 and between an elongated underguide or table 12 and an overlying floating guide or deflector plate 13. The latter may be of a generally similar character as in my patent referred to, said two guides 12 and 13 together providing a throat or feed passage for the tape.

The forward movement of the tape is effected by rotary feed means engageable with its op-

posite faces. The tape feeding means here includes a lower or inner feed wheel or roll 15 fixed on a shaft 16 rotatably supported between the side frames 1. This lower feed member 15, which is driven through its shaft 16 and suitable connections such for example as fully illustrated in my parent application, with a manual operating lever, not necessary to show here, and is engageable with the under face of the tape, its gummed face, through an appropriate recess in the under guide 12. The tape conducting, moistening and delivering means of the present invention are equally adapted for use with other than manually operated tape dispensers, including machines of the motor driven and semi or full automatic classes. Opposite said driven feed wheel 15 and in position to engage the top face of the tape through a similar recess in the upper guide or floating plate 13, is a cooperating upper or outer feed wheel or roll indicated as a whole by the numeral 17.

This upper or outer rotary feed element 17 may be of a construction generally similar to that disclosed in my said patent, including an outer annular tire-like member surrounding a stud shaft 18 and having friction-reducing bearing means interposed between it and said shaft. Said stud shaft is carried on a foot or projection 19 at the base of a lever 20 having a bearing collar 21 on a cross shaft 22. Pins 23 hold the lever 20 in position on said shaft accurately to align the upper feed wheel 17 with the lower one.

The upper feed wheel 17 is normally held yieldingly in operative relation with the lower wheel 15, to grip and feed the tape between them, as by a spring 24 having one end attached to the upper end of the lever 20 and its other end secured to the machine framing as at 25. Said lever 20 extends upwardly between the side frames to a point where it is readily accessible for engagement by a finger of the operator, as indicated at 1, Fig. 1, and has a finger piece or knob 26 for such engagement.

By thus engaging and depressing the lever the upper feed wheel unit 17 is retracted or lifted away from the under wheel 15 into a position such as represented in dotted lines in Fig. 1. This ready separability of the feed wheels at the will of the operator facilitates threading the tape to and between them when a fresh roll supply is to be installed. Further, this manual retraction of the upper feed unit exposes the underlying parts and permits the floating deflector plate 13 readily to be withdrawn bodily, for inspection

or cleaning of the tape guides and associated parts. Release of the finger piece 26 of the lever 20 automatically restores the feed wheels to operative feeding relation. A rearward extension 27 of the foot 19 of the lever 20 acts as a limiting stop for the return of the wheel 17, by engagement with the upper guide plate 13, avoiding injury to the surfaces of the feed wheels when no tape is present between them. Said stop 27 also confines the upper guide or deflector plate 13 against undesired vertical displacement. Claims relating more especially to the tape feeding mechanism are contained in a separate divisional application Ser. No. 320,301 of my said parent application, Serial No. 242,936, while claims mainly involving the cutting or severing means such as herein shown and sufficiently to be described for the purposes of the present application, or involving said severing means in association with feeding features are contained in my said parent application.

The tape T is advanced by the feeding means forwardly through the channel provided between the lower and upper guides 12, 13, to and past suitable means for severing the tape into the desired lengths. The severing means herein comprises a fixed element 60 horizontally disposed crosswise the machine, in substantial continuation of the under-guide 12, and supported on the side frames as by lugs 61 thereon and on which said element is detachably held as by screws 62. The front portion of the guiding and cutting element 60 may serve as a cutting edge for cooperation with a movable blade or cutter, indicated as a whole by the numeral 64, of the guillotine type, adapted to be moved across the path of the tape, herein downwardly from above, to shear the tape. The blade proper 64 may be variously shaped at its cutting edge, and may be formed of one or more parts, secured as by screws 65 to a blade-carrying block 66. At one or both side portions the knife 64 has a depending finger such as seen at 68 to which may be attached spring means 70 adjacent the corresponding side frame and secured thereto as at 71. Such spring means may be employed where a biasing or shearing effect is desired or may be omitted, the guillotine-like cutter 64 being effective to sever the tape by movement across the tape path and substantially perpendicular to the tape. Said depending fingers such as 68 of the guillotine blade also act as vertical guides for the latter, whereby it is confined and guided for movement of the guillotine type in a given plane, herein substantially vertical and perpendicular to the path of the tape.

Said cutter element 64, including the carrier block 66, is pivotally connected, as by pins at the opposite ends of said block, to a supporting yoke 74 of general U-formation, one such pin being indicated at 72. This yoke in turn is supported by its rearwardly extending arms which are pivoted for vertical movement on the cross shaft 22 previously described in connection with the upper feed wheel 17. Thus the cutter assembly including the blade or cutter 64 on the carrier block 66 and the yoke 74 has a horizontal pivotal axis provided by the cross shaft 22 but the cutter proper 64 has substantially a straight vertical movement in parallelism with itself by reason of the pivot pins such as 72 connecting its carrier block to the yoke. Said cutter assembly as a whole is normally held up in raised position clear of the tape path, as by means of one or more springs, one of which is indicated at 76, being attached

at one end to the cutter yoke 74 and being held at its other or upper end on a stud or the like on the adjacent side frame, as at 78. The cutter device may be operated by any suitable means, 5 such as in my parent application, and not necessary to describe more fully here. Forwardly beyond the severance point the tape path continues between a bottom guide plate 90 and an overlying deflector or guide plate 91. The latter 10 has lateral bosses or positioning elements 92 at its front portion, see Fig. 2, for pivoting it on a pin 93 held on the side frames in blocks 94. The pin 93 also serves to support rotatably and with capacity for vertical movement, a roller guide 15 means or element 95 composed of one or more longitudinal units or rollers, preferably of the corrugated or circumferentially grooved form as illustrated. Said rotary guide element 95 constitutes tape presser means adapted to rest by gravity on the upper face of the tape, to cause the latter to pass with its under and gummed face in moistening relation with the underlying moistening means.

As here shown, the moistening means is of the 20 capillary or wick type, including one or more inverted brushes or brush sections 96, 96 upstanding from a liquid reservoir 97 removably positioned between the side frames 1. Said rear and forward brush sections or portions 96, 96 may be 25 constructed otherwise than with separate butt portions as illustrated in Fig. 1 merely by way of example. The described tape guide means including the deflector plate 91 and guiding presser means 95 operatively associated with the moistener means 96 may be similar to that more 30 fully disclosed and claimed in my Patent No. 2,138,474, dated November 29, 1938, resulting from an application copending with my said application Serial No. 242,936 of which this present 35 application is a division.

In the machine of my present invention auxiliary guiding and presser means is provided at the tape delivery point, in advance of the guide element 95. For this purpose a transverse pin 98 40 is provided at a point beyond the deflector and presser assembly 91-95, said pin being held on the side frames in a forward extension of the side blocks 94. This front pin 98 positions for free rotation a further rotary presser or guide element 99, which also may be composed of one or more 45 longitudinal units. As in the guide element 95, the bearing apertures in the roller or roller units of said auxiliary element 99 are of larger diameter than their positioning pin 98, allowing said 50 element to have a vertical floating movement and to rest by gravity on the upper face of the underlying tape.

This supplemental forward guiding and presser element 99 preferably also is formed with a 55 series of circumferential grooves, see Fig. 2, and the positioning pins 93, 98 are so disposed relatively to each other that the two rotary elements 95 and 99 intermesh, their annular ribs 95a and 99a being receivable each in the grooves of the other. The tape contacting portions of the two 60 roller elements are thus brought into close proximity with each other lengthwise the machine, insuring an effective guiding of the tape but with a minimum of frictional resistance thereon. It 65 will also be noted, especially by reference to Fig. 2, that the annular ribs 95a of the rear element 95 have flat circumferential surfaces, of appreciable width, whereas the annular members 99a of the forward roll means 99 are V-shaped in 70 section, having a relatively thin outer edge. Thus

I provide in this instance a substantially greater total contact for the rear guide roll means 95, transversely of the tape and at the zone where the gummed face of the tape first comes in contact with the moistening means, than for the forward guide roll means or elements 99. In other cases the two roll means may be reversely arranged or may be similar or substantially so, depending somewhat on the character and weight of the tape and the quantity of moisture which it is desired to apply to it.

The pin 98 for said forward presser element 99, substantially at the tape delivery point, is herein further utilized as a pivot support for hinging the forward cover plate 100. Said cover is adapted to be received on and between the side frames, normally to close in the operating parts at the front portion of the machine. It may extend rearwardly for the full length of the machine or be supplemented by a similar cover part overlying the rear portion of the tape well and pivoted at the back part of the machine frames or housing. As here represented, said cover plate 100 has fingers 101 at its lower edge pivotally received on said pin 98, allowing the cover to be swung between its closed full-line position of Fig. 1 and an open position as represented in dotted lines in said figure. The underlying parts are thus readily accessible, for adjusting the tape and for cleaning and inspection purposes, including particularly the deflector plate 91 (noting its dotted elevated position in Fig. 1), the finger lever 20 of the upper feed roll 17, the removable top guide plate 13 and the other associated parts. Said cover 100 is not fully opened in said dotted position of Fig. 1 and may be swung forwardly to the left in said figure, substantially into a horizontal position, until held by shoulders 102 on the cover-supporting fingers 101 coming into engagement with the inner pin 93 already described and which accordingly may have this additional cover positioning function.

My invention is not limited to the particular embodiment thereof illustrated and described herein, and I set forth its scope in my following claims.

I claim:

1. In a machine of the class described, a frame providing support for a tape supply to be delivered in moistened lengths, guiding means defining a path for the tape, moistening means underlying the tape path adjacent the delivery point and comprising an inverted brush device having rear and forward sections, a plurality of parallel guide rollers rotatably supported one behind another substantially opposite the moistening means and having capacity for vertical yielding movement so as to float on the upper face of the tape to be moistened, said brush device cooperating with the plurality of rollers in vertical opposition thereto.

2. In a tape dispensing machine, in combination, a frame, a moistener thereon for the gummed under face of the tape, under and upper guides providing between them a tape path to the 65

moistener, a plurality of pins stationarily supported by the frame and extending transversely of the tape path approximately vertically opposite the moistener, and a corrugated roller positioned by each pin for vertical yielding movement so as to float against the underlying tape, the corrugations of each roller intermeshing between those of the other.

3. In a tape dispensing machine, in combination, a frame, a moistener thereon for the gummed under face of the tape, under and upper guides providing between them a tape path to the moistener, the upper guide comprising a plate pivotally supported at its front portion adjacent the moistener, and a plurality of parallel roller elements disposed one behind another, with the rear element adjacent said front portion of the pivoted plate, said elements positioned to float on the upper face of the tape passing over the moistener and each having a series of circumferential alternating ribs and grooves, the axes of said elements being so disposed that the ribs of one element mesh respectively in the grooves of another.

10 4. In a tape dispensing machine, in combination, a frame including spaced side members, a support for a tape supply, tape feeding means to advance lengths of the tape along a path between the side frames, a moistener for the under face 15 of the tape, a plurality of guide rolls extending transversely of the tape path above the moistener, one roll behind another, means for rotatably supporting the rolls on the frame with capacity for vertical yielding movement so that they float 20 on the tape crossing the moistener, and a cover plate pivoted on the frame coaxially with the support for one of said rolls and adapted to cover the space between the side frames above said moistener and feeding means.

25 5. A tape dispensing machine according to claim 2 including in combination a top cover having a hinge connection at its forward portion, said connection being pivotally received and positioned by one of the transverse pins.

30 6. A tape dispensing machine according to claim 4, including abutment means on the cover engageable with the support for the other of the guide rolls, to limit and support the cover in open position.

35 7. In a machine of the class described, a frame providing support for a tape supply to be delivered in moistened lengths, guiding means defining a path for the tape, a capillary moistening element below the tape path adjacent the delivery point, a plurality of parallel transverse guide rollers rotatably supported one behind another substantially opposite the moistening element and having capacity for vertical yielding movement so as to float on the upper face of the tape to be moistened, and annular ribs distributed along each of a plurality of said rollers, said ribs of one roller being wider at their outer portions than those of another.

TREVOR R. GAUTIER.
